UNBUTTONING DEVICE

John M. Whelton, Peabody, Mass., assignor to
 United Shoe Machinery Corporation, Paterson,
 N. J., a corporation of New Jersey

Application September 25, 1933, Serial No. 690,819

26 Claims. (Cl. 12—151)

This invention relates to devices for unbuttoning shoes and is herein illustrated as embodied in devices designed for unbuttoning the uppers of shoes which have been buttoned and lasted 5 and have come to the operator upon the last.

In the manufacture of buttoned shoes the upper is usually buttoned prior to lasting and in that operation the buttoned upper is conformed tightly to the last with the result that the fastening 10 supplied by the button or buttons is placed under considerable tension. As the manufacturing process progresses it becomes necessary to unbutton the upper while it is still tensioned upon the unyielding last, an operation requiring the application of considerable strength and the exercise 15 of skill in order to avoid tearing out the buttonhole, ripping off the buttons, or otherwise damaging the upper. Many women's shoes are made which have one or more cross straps detachably 20 secured by buttons. In this case also the operator frequently does the unbuttoning with his fingers, primarily by pulling upwardly the buttonhole flap or the strap. This way of going at it, however, brings the buttonhole directly into engagement 25 with the flat under side of the button, where the greatest resistance to the unbuttoning operation is afforded, and puts a serious strain upon the thread or staple which has been used to attach the button. Frequently the unbuttoning 30 operation occurs immediately before the last-pulling operation. An important field of use for the present invention, accordingly, is unbuttoning lasted uppers preparatory to the last-pulling operation and the specific embodiments 35 of the invention herein shown are designed for such use.

One object of the present invention is to provide an improved device for unbuttoning shoes by means of which the work may be done more expeditiously and with less danger of damage to 40 the shoe.

This object may be accomplished, in accordance with a feature of the invention, by providing the device with a button-engaging means or abutment, together with cooperating jaws for gripping the button hole flap adjacent to a button-hole, means being provided for producing relative movement between the jaws and the button-engaging means to bring the flap into engagement 45 with the rounded edge of the button and then past the button.

In accordance with still another feature of the invention, means are provided for moving the button-engaging means to bring the button into 50 edgewise relation to the buttonhole flap, thereby

facilitating the spreading of the buttonhole by the rounded edge of the button.

Another feature of the invention consists in a device embodying a single operating member arranged in its continuous movement in one direction to bring about the desired sequence of related steps. For example, a hand- or treadle-operated lever is herein shown as acting in its initial movement to bring the pair of cooperating jaws into gripping engagement with the buttonhole flap, further movement being effective to move the closed jaws to pull the buttonhole over the button. In one embodiment, the movement of the lever is also effective to tilt the button toward the buttonhole, to bring it in edgewise position, before the flap is pulled over the button. 5 10 15

The mechanism of my invention may be embodied in a hand-operated or in a treadle-operated device in accordance with the requirements of the use to which it is to be put or the convenience of the operator. It is herein shown as embodied in two generically alike but specifically different devices which may be installed adjacent to last-pulling machines and to which the operator may present the buttoned and lasted upper 20 25 just prior to the last-pulling operation.

These and other features of the invention will be best understood and appreciated from the following description of two preferred embodiments thereof selected for purposes of illustration and shown in the accompanying drawings, 30 in which

Fig. 1 is a view in side elevation of one embodiment of the device, showing a lasted shoe in section in the position which it occupies when presented to the device;

Fig. 2 is a similar fragmentary view showing the parts in the position which they occupy near the conclusion of the unbuttoning operation;

Fig. 3 is a fragmentary view in front elevation; 40

Fig. 4 is a view in side elevation of another embodiment of the device of alternative construction;

Fig. 5 is a detail view in section on an enlarged scale on the line V—V of Fig. 4; and 45

Fig. 6 is a sectional view of a lasted upper and the coacting parts of the device during the unbuttoning operation.

Referring first to Figs. 1 to 3, it will be seen that the moving parts of this embodiment of the device are operated by a hand lever 26 and are supported upon an overhanging bench bracket 10, being carried by two journal studs 12 and 14 which project from the face of the bracket. A lifter lever 16 is pivotally mounted upon the 50 55

5 rearmost stud 14, extending upwardly and forwardly therefrom and provided on opposite sides with stop lugs 17 and 18 which cooperate with fixed ears projecting outwardly from the frame 10 and serving to limit the amplitude of swinging movement of the lever 16 about the axis of the stud 14. The lever 16 is forked in its upper end and provided near its end on its left-hand branch, as seen in Fig. 3, with a projecting shoulder 19 for a purpose which will be presently described. The lower end of the lever 16, which acts as a lifting lever, is widened and extended slightly below its journal stud 14 where it is provided with a forked lifter comprising a plate 20 secured to the bottom of the lever 16 by screws and being tapered and forked at its forward end to form a thin jaw 22. The jaw 22 of the lifter plate 20 is shaped to be inserted between the strap or flap of the lasted upper and the body 25 of the upper which is to be unbuttoned. It will be apparent that when the lever 16 is swung in a clockwise direction from the position shown in Fig. 1 to that shown in Fig. 2, the stop lug 18 limiting this movement, the forward end 22 of the lifter is swung upwardly about the axis of the bearing stud 14.

30 An upper 102 lasted upon a last 104 is shown in Fig. 1 and is represented as having a strap 100 in which is formed a buttonhole which is buttoned over a button 106 secured to the upper. In presenting such an upper to the device the forked end of the lifter is positioned beneath the strap 100 and upon the surface of the upper in position to straddle the shank of the button 106.

35 Pivotedly mounted upon a pin 24 extending transversely between the forks of the lever 16 is the hand lever 26 having a forwardly extending arm 27 and a rearwardly extending arm 28. The forwardly extending arm 27 is provided with 40 a stop lug 29 which engages with the shoulder 19 of the lever 16. A tension spring 30 is connected to the front end of the arm 27 and at its lower end to a stud 32 projecting outwardly from a boss 34 on the face of the bracket 10. 45 The action of the spring 30 maintains the stop lug 29 in engagement with the shoulder 19 and tends always to swing the lever 16 forwardly or in counterclockwise direction, establishing its initial position by holding the stop lug 17 in contact with the corresponding ear on the frame 10. 50 The rear arm 28 of the lever 26 is connected by a pivot pin 48 and link 42 to the head 44 of a downwardly extending rod 46 encircled by a compression spring 48 and fitting telescopically 55 at its lower end within a sleeve 50 having a collar 52 about its upper end. The sleeve 50 at its lower end is pivotally connected by a stud 54 to an arm 56 which in turn is pivotally connected by a pin 58 to an ear 15 projecting outwardly from the lever 16 at a point opposite its journal stud 14. The forward end or jaw 60 of the arm 56 is forked and otherwise shaped to correspond with the forked end 22 of the lifter, these two elements cooperating as a pair of jaws 65 to grip the material of the end of the strap 100 to be operated upon.

60 The rod 46 carries a transversely extending pin 62 which projects outwardly through a slot 64 in the sleeve 50 and limits the relative longitudinal movement of the rod and sleeve. The tension spring 30, in rocking the hand lever 26 forwardly or in counterclockwise direction, tends always to lift the rod 46 and the initial position of the latter is determined by the engagement 70 of the pin 62 with the upper end of the slot 64.

When the hand lever 26 is rocked rearwardly and the rod 46 depressed, the pin 64 travels downwardly to some such intermediate position as that indicated in Fig. 2 and downward pressure is yieldingly imparted to the sleeve 50 through the compression spring 48 to move the forked jaws 22 and 60 into gripping engagement with the strap 100 interposed between them.

75 A swing piece 35 is pivotally mounted on the stud 12 and, as shown in dotted lines in Fig. 1, 10 has a downwardly extending arm 36 provided with a finger 37 which passes between the forks of the jaws 60 and 22 into position to engage the rear side of the button and act as a limit stop, abutment, or positioning member therefor 15 when the upper is presented to the device. The arm 36 also has an inclined abutment surface 41 which cooperates with the vertical surface of the finger 37. The swing piece has also a rearwardly extending arm 38 which is received in a slot in 20 the lower end of the rod 46 and is arranged to engage an ear 39 projecting outwardly from the bracket 10 and thus to limit the rocking movement of the swing piece in a clockwise direction. The arm 38 is also provided with a pin 66 which 25 projects into a slot 68 in the rod 46 and determines the initial position of the swing piece by engaging the lower end of this slot. After the upper has been presented in the position shown in Fig. 1, and as the rod 46 is depressed in the 30 operation of the device, and the lost motion of the slot 68 has been taken up, the swing piece is rocked in a clockwise direction and the button is tipped forwardly and its head is positioned with its rounded edge toward the buttonhole 35 flap.

35 In operating the device above described, the operator presents the buttoned and lasted upper in the position shown in Fig. 1 wherein the upper rests against the under side of the plate 20 and the 40 forked lifter jaw 22 lies between the buttonhole strap and the body of the upper 102 to which the button is secured, said jaw straddling the button shank. The upper is moved rearwardly until the button engages and is positioned with respect to 45 the jaws by the finger 37 acting as an abutment or stop. In this position the forked jaw 60 of the arm 56 is located above and also straddles the button and the finger 37 of the swing piece engages the rear side of the button 106. Having 50 thus presented the upper, the operator swings rearwardly the hand lever 26, pressing down the rod 46 and yieldingly forcing the sleeve 50 downwardly and by this means depressing the forked jaw 60 into gripping engagement with the strap 55 100 near its end. When the strap 100 has thus been securely gripped, the swing piece 35 is moved forwardly, by engagement of the upper end of the slot 68 in the rod with the pin 66. The finger 37 on the arm 36 thereupon tilts the button 106 to 60 the left, as indicated in Fig. 2, to position the edge of the button to the buttonhole and to hold it there. Further movement of the hand lever 26 in the same direction thereupon swings the lifter lever 16 on the stud 14 until the lug 18 strikes the 65 adjacent ear. The material of the strap 100 about the buttonhole is thus carried yieldingly upwardly past the button, being grasped by the jaws at points spaced from each side of the button, with the result that the curved surface of the button 70 spreads open the buttonhole and finally the lifter jaw 22 is effective to pull the buttonhole past the button. The button is meanwhile held in its tilted position (Fig. 2) by the abutment 41 of the finger on the swing piece 35 which latter has now 75

reached its final position determined by the engagement of its arm 38 with the ear 39. In the final part of the continued progressive rearward movement of the hand lever 26, the stop lug 18 of the lifter lever is carried into engagement with its limiting ear on the bracket 10, the unbuttoning being complete. Upon releasing the hand lever 26, the parts are all restored to their initial position by the action of the springs 30 and 48, the upper is released, and the device is in readiness to be again used.

The embodiment of the device, shown in Figs. 4 to 6 and which includes the same broad features of the invention exemplified in the form already discussed, will now be described. This comprises an upright frame or stand 10 adapted to be secured to a bench and having formed integrally therewith a horizontally disposed boss 12 adapted to provide a bearing for the operative instrumentalities of the machine. In this bearing is rotatably mounted a tubular shaft 74 carrying at its outer end a head 76 having a portion thereof extending to form the relatively fixed jaw 78 of a cooperating pair which are designed to grip the strap or flap having the buttonhole. The jaw 78 is provided with a transverse button-engaging stop or abutment 79, shown in Fig. 6 as normal to the jaw face and integral with the jaw 78, and designed to engage the head of the button and act as an abutment while the buttonhole is pulled over it, as will presently appear. The lower and movable jaw 80 is pivotally supported in the head 76 by a pin 81 and is formed as a lever having a rearwardly extending arm 82. This is connected through a pin 83 to a toggle link 84 and a tension spring 85 tends at all times to straighten the toggle and thus swing the movable jaw 80 downwardly into its open position.

The toggle link 84 at its inner end is connected by a pin 86 to the outer end of an operating rod 88 which is arranged to slide longitudinally or axially in the tubular shaft 74. The rod 88 extends entirely through the shaft 74 and is engaged at its rear end by a yielding contact plunger 89 carried in the lower end of an operating lever 90 which is journaled to swing about a horizontal journal 91 set in the frame 10. The operating lever 90 carries a cam roll 92 at its upper end which is arranged to run upon a cam surface 93 formed upon the rear arm of a cam lever 94. The cam lever 94 is mounted upon a journal pin projecting from the upper part of the frame 10 and is connected at its forward end to a treadle rod 95. A tension spring 96 serves at all times to rock the operating lever 90 in a counterclockwise direction, as viewed in Fig. 4, and hold the cam roll in contact with the cam surface 93. This cam surface is designed, early in the throw of the lever 94, to rock the operating lever in a clockwise direction, advancing the rod 88 toward the left, breaking the toggle in opposition to the tension spring 85 and swinging the jaw 80 upwardly into closed position to grip the work near the buttonhole. This movement is effected through a train of mechanism which includes the contact plunger 89 backed up by a strong compression spring and this introduces a slight yield into the closing action of the jaws.

The tubular shaft 74 is provided near its inner end with a pinion 97, the latter being formed integrally with a collar 98 and secured therewith to the shaft by a set screw. The pinion 97 meshes with the teeth of a rack 99 mounted to reciprocate vertically in bearings provided therefor in the frame 10. At its upper end the rack 99 is pivotally connected to a link 73 and this in turn

has a pin-and-slot connection to the cam lever 94. The slot provides a lost-motion connection between the two permitting the treadle lever to move sufficiently to rock the operating lever 90 and close the jaws 78-80 before any vertical movement is imparted to the rack 99. When the lost motion has been taken up, the rack is moved upwardly and the pinion 97 rotated to turn the shaft 74 and the whole jaw assembly through substantially 180°.

The operation of the device will be best understood by reference to Fig. 6, wherein are shown the jaws 78 and 80 in the position which they occupy toward the conclusion of the unbuttoning operation. The lasted upper is presented to the device so that the end of the strap 100 or the flap in which the buttonhole is formed is inserted between the open jaws, the parts being in the position shown in Fig. 4. The operator then depresses the treadle rod 95, first rocking the operator lever 90 to close the jaws into gripping relation with the end of the strap as already explained. Continued depression of the treadle thereupon begins to move the rack 99 upwardly and turn the jaw assembly, bringing the stop 25 surface 79 of the upper jaw into abutting relation to the top of the button 106 and thus resisting displacement by the strap 100. With the button so held, continued turning movement of the jaws acts to spread the buttonhole over the 30 circular periphery of the button and thus complete the unbuttoning operation. During this turning movement, the relative positions of the jaws and the abutment surface 79 in space are continually changing. When the treadle rod is 35 released, it is drawn up by a spring (not shown) and the lever 94 is rocked in a clockwise direction (as viewed in Fig. 4), first rotating the jaw assembly to its initial position and then, when the lost motion has been again taken up, reversely rocking the operating lever 90 and releasing the rod 88 so that the spring 85 may again open the lower jaw 80 in readiness for another operation.

Having described my invention, what I claim as new and desire to secure by Letters Patent of the United States is:

1. An unbuttoning device comprising means for gripping a buttonhole flap by engaging opposite faces of the flap, button-engaging means, and means for producing relative movement between said gripping means and said button-engaging means to bring said flap into engagement with the under side of the button and then past the button.

2. An unbuttoning device comprising cooperating jaws for gripping opposite faces of a buttonhole flap adjacent to a buttonhole, button-engaging means, and means for producing relative movement between said jaws and said button-engaging means to bring said flap into engagement with the periphery of the button at the buttonhole and then past the button.

3. An unbuttoning device comprising means abutting a button upon an upper at a point away from the upper, to hold it, and gripping means for engaging the buttonhole flap in spaced relation to the button and pulling the flap outwardly while the button is so held.

4. An unbuttoning device comprising cooperating jaws operative to grip the buttonhole flap of an upper adjacent to a button fastening the upper, angularly movable means for engaging the button on a side thereof away from the upper, and means for forcibly moving the closed jaws 75

with the flap engaged between them to pull the flap toward the other side of the button while the button is so engaged.

5. An unbuttoning device comprising a thin jaw arranged to be positioned between the buttonhole flap and the body of a lasted upper adjacent to a button fastening the same, a jaw cooperating with the thin jaw to grip the flap, an abutment associated with the jaws for engaging the button, means for closing said jaws to grip the flap, and means for imparting a movement of translation to the jaws and the gripped flap to press said button toward the abutment and to pull the flap outwardly over the button.

10 6. An unbuttoning device comprising cooperating jaws for gripping the buttonhole flap of a lasted upper adjacent to a button fastening the upper, means engaging the button on a side thereof away from the buttonhole flap, and 20 mechanism for first closing the jaws to grip the flap and then bodily moving said jaws and buttonhole flap past the button positioned by said engaging means.

25 7. An unbuttoning device for buttoned uppers comprising a pair of jaws cooperating to grip the buttonhole flap of the upper, a button stop, and a single operating device movable first to close said jaws and then bodily to move the jaws in closed condition relatively to said stop.

30 8. An unbuttoning device comprising cooperating jaws for engaging the buttonhole flap of an upper adjacent to a button fastening the upper, means engaging the button on a side away from the upper, and mechanically operated mechanism for first closing and then bodily twisting said jaws.

35 9. An unbuttoning device comprising an oscillatory head carrying cooperating jaws for engaging the buttonhole flap of a buttoned upper, cam-operated means for controlling the position of the jaws, including a rod axially movable with respect to the head, and means for twisting the head while the jaws are closed.

40 10. An unbuttoning device comprising an oscillatory head carrying cooperating jaws for engaging the buttonhole flap of a buttoned upper, cam-operated means for closing the jaws and maintaining them closed, and related mechanism for turning the head to twist the jaws first in one direction and then in the other before the jaws are released.

45 11. An unbuttoning device comprising a tubular oscillatory shaft having a head, cooperating jaws mounted in the head, one of the jaws having a button-holding element associated therewith, an operating rod movable axially therein for closing the jaws, and mechanism including a treadle lever arranged to move said operating rod and to oscillate said shaft with said jaws.

50 60 12. An unbuttoning device comprising a stand presenting a pair of horizontally disposed jaws, a treadle lever pivotally mounted on the stand, a rotatably mounted tubular shaft journaled in said stand and carrying said jaws at its outer end, a jaw-closing mechanism including a cam lever and an operating rod slideable within said shaft, and a jaw-twisting mechanism including a rack and a pinion connected to said shaft.

65 70 13. An unbuttoning device comprising cooperating jaws for gripping between them the buttonhole flap of a lasted upper adjacent to a button fastening the upper, button-engaging means movable to bring said button into edgewise relation to said flap, and means for causing relative movement between said button-engaging means

and said jaws to cause the buttonhole to pass out over a rounded part of the button.

14. An unbuttoning device comprising a thin jaw arranged to be positioned between the buttonhole flap and the body of an upper adjacent to a button fastening the same, a cooperating jaw acting to grip the flap, said jaws being mounted for movement toward and away from each other and for movement of translation, means associated with the jaws for engaging the top 10 of the button and tipping one edge thereof toward the upper, and means for thereafter moving the jaws in gripping relation, while the button is so tipped, to pull the flap outwardly and off the button.

15. An unbuttoning device comprising a projecting forked jaw whereby a buttoned upper may be engaged and located with reference to any selected button fastening it, a jaw cooperating therewith to grip the buttonhole flap, a member for tilting the button toward the upper, and means producing relative movement between the closed jaws and said button-tilting member while the button is held by the latter.

16. An unbuttoning device comprising a forked 25 jaw mounted in position to straddle the shank of a button fastening an upper, a stop for engaging the advancing side of the head of the button as the upper is presented to the device, means cooperating with said jaw to grip the buttonhole flap and for thereafter moving the stop to tilt the button toward the upper while the flap is so held.

17. An unbuttoning device for buttoned uppers comprising a single actuating element and 35 the following mechanism arranged to be operated thereby in the proper sequence, viz., cooperating jaws for gripping the buttonhole flap between them, a button-tilting member, and mechanism for moving the closed jaws with respect 40 to said member.

18. An unbuttoning device comprising jaws for gripping the buttonhole flap of a buttoned upper, a button-tilting member, and means operative in one progressive movement to cause said device to grip the buttonhole flap, to tilt the button, and then to unbutton the upper.

19. An unbuttoning device for buttoned uppers comprising a lifting lever having a jaw shaped to straddle the shank of a button fastening the upper, a jaw cooperating therewith to grip the buttonhole flap of the upper, a button-positioning member, and mechanism for moving the lifting lever away from the body of the upper when the button has been positioned.

20. An unbuttoning device for buttoned uppers comprising a horizontally disposed plate having a forked jaw at its outer end shaped to straddle the shank of a button fastening the upper, a button abutment above said plate, a second jaw cooperating with the first to grip the buttonhole flap adjacent to the button, and means for swinging the outer end of said plate toward said abutment to unbutton the upper.

21. An unbuttoning device for buttoned uppers comprising a pair of pivotally mounted arms provided at their outer ends with cooperating jaws for gripping the buttonhole flap of the upper and being normally maintained in substantially horizontal spaced position, a button stop for 70 engaging one side of the button, and mechanism for first swinging said arms toward each other to grip the work and then moving them relatively to said button stop.

22. An unbuttoning device for buttoned uppers

pers comprising a frame, a lever pivoted thereon and carrying cooperating jaws for engaging the buttonhole flap of the upper, and a button stop mounted on the frame and arranged to tilt the button in a direction away from the fulcrum point of the lever while the jaws are moved relatively to the stop.

5 23. An unbuttoning device for buttoned uppers comprising cooperating jaws movably mounted and shaped to engage the buttonhole flap of an upper, means for determining the position of a button with respect to the jaws, and an operating lever yieldably connected to one jaw and movable first to close the jaws and then, 10 at a predetermined degree of closing pressure, to move the closed jaws with the flap relatively to said positioning means.

15 24. An unbuttoning device for buttoned uppers comprising forked cooperating jaws movable relatively to grip the buttonhole flap of an upper adjacent to a button fastening the upper, a button stop arranged to pass through the jaws behind the button and to tilt the button toward the open end of the jaws, and means for moving 20 the jaws with the gripped flap relatively to the stop while the button is held tilted thereby.

25. An unbuttoning device for buttoned uppers comprising a jaw-carrying lever having an arm pivotally mounted thereon and provided with a second jaw, a button stop, and an operating lever pivotally mounted on the jaw-carrying lever and having a yielding connection with said arm whereby, in the continued movement of the operating lever, the jaws are first closed and then moved bodily with respect to said stop.

26. An unbuttoning device for buttoned uppers comprising a frame, a lever pivotally mounted thereon and carrying relatively movable jaws shaped to engage a buttonhole flap of the upper adjacent to a button fastening the upper, a button stop pivotally mounted on the frame and 15 extending initially into one of said jaws to about a button therein, an operating lever mounted on the jaw-carrying lever and having a yielding connection with one of said jaws whereby the jaws are closed in the initial movement of the 20 operating lever and then moved simultaneously, and connections between said operating lever and said button stop whereby the latter is swung toward the open end of the jaws as they are moved with the gripped flap.

25 JOHN M. WHELTON.
